PNEUMATIC MOTOR

Charles S. Tankersley, Harlingen, Tex.

Application February 28, 1933, Serial No. 659,005

7 Claims. (Cl. 121—34)

This invention relates to new and useful improvements in pneumatic motors.

One object of the invention is to provide a pneumatic motor which may be made sufficiently light in weight and small enough in size to be readily handled by a single workman for performing various operations, such as operating a wrench for tightening nuts and bolts, or other small tools, or for applying power where work 10 is usually done manually, such as the cranking of airplane motors and the like.

A particular object of the invention is to provide a motor having a reversing valve arranged so as to be quickly and easily operated, and especially one in which the same ports are used for driving in either direction, thus eliminating a dual set of ports or passages.

An important object of the invention is to provide an air motor of the light portable type, 20 in which stuffing boxes and similar packing elements are entirely eliminated, whereby the motor is made substantially air-tight and is not likely to be distorted or sprung when dropped and thereby cause air leaks either within or without 25 the casing.

Another object of the invention is to provide a valve mechanism wherein the fluid pressure is utilized to hold the controlling elements in contact and to prevent leaks therebetween.

A still further object of the invention is to provide an air motor in which the exhaust fluids are conducted to a separate chamber within the casing and thus excluded from the crank case; and also wherein the actuating means for reversing the valve is located in the exhaust chamber, which eliminates the necessity of packing, particularly in connection with the operating 35 lever.

Another object of the invention is to provide 40 an air motor in which the power takeoff or tool connection is located at the outer margin of the motor, whereby work in corners and angles may be done; and in connection with an oppositely directed handle an increased leverage 45 obtained.

A further object of the invention is to provide a valve mechanism and a drive therefor in which wear is automatically taken up and leaks which would otherwise result are eliminated.

50 A construction designed to carry out the invention will be hereinafter described, together with other features of the invention.

The invention will be more readily understood from a reading of the following specification and 55 by reference to the accompanying drawings, in

which an example of the invention is shown, and wherein:

Figure 1 is a rear elevation illustrating a pneumatic motor constructed in accordance with my invention, 60

Figure 2 is a fragmentary front elevation partly in section and illustrating the reduction gears for the motor.

Figure 3 is a side elevation illustrating the 65 motor,

Figure 4 is a fragmentary vertical sectional view showing the interior of the motor and the control valve for automatically regulating the pneumatic pressure to the cylinders and also regulating the exhaust from said cylinders, 70

Figure 5 is a fragmentary plan view showing the valve positioned to admit pressure to one of the cylinders and to exhaust the other cylinder,

Figure 6 is a sectional view taken on the line 6—6 of Figure 4, 75

Figure 7 is a fragmentary sectional view showing the relative position of the pistons of the cylinders,

Figure 8 is a plan view illustrating the rotatable cap or plate of the control valve, 80

Figure 9 is a plan view illustrating an opposite face of the cap or plate from that shown in Figure 8,

Figure 10 is a plan view illustrating the intermediate plate of the valve, 85

Figure 11 is a plan view illustrating the shifting spider or plate of the valve,

Figure 12 is a fragmentary sectional view illustrating the handle for manipulating the device and controlling the main valve, 90

Figure 13 is a detail sectional view illustrating one of the pistons of the motor,

Figure 14 is a detail view illustrating an oil groove to establish communication between the lubricant chamber and the air supply passage of 95 the device,

Figure 15 is an enlarged diametrical sectional view through the valve and component parts of the motor,

Figure 16 is a vertical sectional view taken on 100 the line 16—16 of Figure 15, and showing the valve mechanism shifted for operating the motor in a clockwise direction, and

Figure 17 is a similar view showing the valve mechanism adjusted to drive the motor in a 105 counter-clockwise direction.

Referring in detail to the drawings, the numeral 1 indicates a cylindrical crank case having formed integrally therewith radially extending cylinders 2 in which are reciprocally mounted 110

pistons 3 carrying removable connecting members 4 to which connecting rods 5 are pivoted. The inner end of each connecting rod is formed integrally with said rod and surrounds and supports 5 an anti-friction bearing 6 which receives the crank 7 of a crank shaft 8 located centrally of the crank case. It is to be noted, however, that the outer ends of the cylinders are shown integral with said cylinders. This eliminates packing 10 gaskets which are required when removable heads are used, and the danger of rupturing or displacing the head when the motor is dropped or roughly used, is avoided. The ends of the crank case are closed by removable heads 9 and 15 10 equipped with bearings 11 that rotatably support the crank shaft.

A gear housing 12 is removably secured to the head 10 and extends parallel with one of the cylinders to the outer end thereof. The head 10 20 also is provided with an extension which extends parallel with the cylinder above referred to and cooperates with the cover of the gear housing in enclosing a train of speed reducing gears 13, one of which is secured to the crank shaft while 25 another is secured to a power take-off shaft 14. The shaft 14 is supported by the extension on the head 10 and by a thrust bearing 15 carried by the cover of the timing gear case. The power take-off shaft may be of any desired construction so 30 that any conventional type of wrench, socket or coupling tool may be connected thereto.

The outer face of the head 9 has formed there-in an annular exhaust recess or chamber 16 communicative with exhaust ports 17 formed in the 35 contiguous walls of the crank case. A valve plate 18 is secured to the crank case over the chamber 16 of the head 9 and is provided with passages 19 in continuous communication with said exhaust. One end of the crank shaft extends through the 40 head 9 and plate 18 into a removable housing 20 secured to the plate 18. The housing cooperates with the plate 18 in forming a chamber 21 in which a control valve mechanism 22 is located, the purpose of which is to control passage of the 45 pressure fluid to and exhaust from the cylinders. Formed integrally and in communication with the housing 20 is a pressure fluid supply pipe 23 connected to a valve case 24 positioned between two of the cylinders. This case is connected to 50 a handle 25 which is suitably secured to the crank case and provides a medium for permitting the operator to easily manipulate the motor and the tool or other device carried by the take-off shaft 14. By observing Figures 1, 2 and 3, it will be 55 noted that the handle and gear train are longitudinally aligned with cylinders on each side thereof, whereby the motor is balanced when the handle 25 is held by the workman.

The handle also provides a medium for conveying air or other pressure fluid to the motor by 60 having its outer end equipped with a fitting 26 to which a hose 27 is connected for supplying a pressure fluid. The handle is in communication with the valve case 24 and the latter has located therein 65 a rotatable valve 28, the stem of which carries a gear segment 29 meshing with a segmental gear 30 on a sleeve 31 journaled on the handle proper. The sleeve is provided with a spiral spring 32 for normally urging the sleeve in a position to close 70 the valve 28 and which will permit the sleeve to be manually turned in one direction for opening the valve to allow pressure fluid to enter the chamber 21. Formed in the handle is a lubricant chamber 33 adapted to be supplied with lubricant 75 through a fitting 34. A pressure fluid conducting

tube 35 extends from the fitting 26 through the chamber 33 to the reduced bore of the handle. Lubricant in limited amounts may pass through a groove 33' located in the tube 35 whence said lubricant may pass into the interior of the motor along with the pressure fluid for lubricating the various moving parts of said motor. Surrounding the tube 35 at the bottom of the lubricant chamber is a felt washer 35' which allows a slow movement of the lubricant into the groove 33'. It is to be understood that the lubricant is in the form of an oil. Communicating pressure fluid ducts 36 are formed in the plate 18 and walls of the cylinders 2. These ducts communicate with the interior of the cylinders at their outer ends and with the chamber 21. The communication between said ducts and the chamber 21 is controlled by the valve mechanism 22.

The valve mechanism 22 consists of an oscillating or shifting circular spider 37, an intermediate disk 38 and a cap or outer disk 39. The spider 37 is formed with an axial sleeve 40 which surrounds one end of the crank shaft and extends inwardly through an opening in the plate 18 into the exhaust chamber 16. A gear 41 fastened on the inner end of the sleeve meshes with a gear segment 42 secured on the end of an operating shaft 43 extending through the plate 18. Because the gear and segment are located in the exhaust chamber, no stuffing box 105 or other packing is required for the shaft 43. An exterior handle 44 is fastened on the shaft and by swinging the handle in opposite directions the spider will be oscillated accordingly.

The spider 37 and intermediate disk 38 have a 110 rotating fit in the housing 21 and this maintains the circular portion of key-hole opening 47 in said disk in registration with the bore of the sleeve 40, whereby constant communication is had between the exhaust chamber 16 and the 115 cap 39, by way of the passages 19 and a port 40' in said sleeve.

The spider is formed with elongated arcuate slots 45 located to register with the ducts 36, one with each of the three ducts. The disk 38 120 has equally spaced ports 46 in registration with the slots 45 of the spider. The rotation or oscillation of the disk 38 is limited by a stud 20' (Figures 16 and 17) carried by the cover 20 and engaging in a peripheral groove 38' in the edge 125 of said disk. Motion is imparted to the disk, when the spider is shifted, by a pin 48 engaging in the bottom of opening 47. The cap 39 has formed centrally thereof an outwardly directed dome 49 and communicating therewith an arcuate channel 50 located, and of such length, as to cover two of the ports 46. The outer edge and under surface of the cap has a turning fit on the disk 38 which may be slightly larger than the cap. The pressure fluid in the chamber 21 will hold the 135 valve members 37, 38 and 39 in such intimate contact as to prevent leaks therebetween as well as preventing leaks between the spider and the plate 18. A helical spring 52 surrounding the dome and engaging the inner wall of the housing 140 20 serves to hold the valve members in place when they are not under fluid pressure. A coiled spring 52' surrounding the sleeve 40 between the plate 18 and the gear 41, acts to urge the sleeve and gear inwardly, thereby holding the spider 37 in 145 intimate contact with the outer face of the plate 18 and also compressing a packing washer against the inner wall of the exhaust chamber, as is clearly shown in Figures 4 and 15.

A cross pin 51 in the dome engages in a notch 150

51' in one end of the crank shaft (Figures 4 and 15) for the purpose of rotating said cap. Because of the length of the slot, wear between the valve members is automatically taken up. It is to be noted that the end of the shaft is covered by the dome 49. As is best shown in Figures 8 and 9, the marginal portion of the cap 39 is formed with an arcuate opening or recess 53 located to successively move over and uncover the ports 46 when the cap is rotated by the crank shaft. Thus two of the ports are constantly covered by the cap while one is open to allow the pressure fluid to pass through to one of the slots 45 of the spider and from thence to one of the ducts 36. During more than one half of each rotation of the cap the channel 50 will be over one or more of the ports 46, and thus communication is established between the ducts 36 and the exhaust chamber 16 by way of the opening 47, sleeve 40, port 40', and passages 19.

In operation, the hose 27 is connected with a suitable source of pressure fluid supply and for the purposes of explanation, it will be assumed that compressed air is the fluid supplied. The handle sleeve 31 is held by the operator in one hand, while the outer end of the handle 25 is held in his other hand. By rotating said sleeve the valve 28 is opened, whereby air is supplied to the chamber 21. One of the ports 46 being exposed by the recess 53 of the cap 39, the air passes through said port to the communicating slot 45 of the spider 37 and thence into the duct 36 which is in registration with said slot as is shown in Figures 4, 5, 15, 16 and 17. The compressed air will flow through the duct 36 to the outer end of its respective cylinder and drive its piston 3 inwardly, whereby rotation will be imparted to the crank shaft and the valve mechanism 22, thus starting the motor.

46 In order to clearly explain the operation of the motor, I have designated in Figures 16 and 17 (only) the ducts 36 as 1, 2 and 3, and the ports 46 as A, B and C. It will be noted that with the motor and the valve member 39 rotating in a clockwise direction (Figure 16) and the disk 38 and spider 37 stationary, the slots 45, which establish communication between the ports 46 and the ducts 36, are in a particular relation. When the valve members 37 and 38 are shifted in a counter-clockwise direction to reverse the valve, the slots 45 are moved so that the slot 45, which in Figure 16 establishes communication between duct 1 and port A, is moved to establish communication (Figure 17) between the duct 1 and the port C. Thus where the air was being supplied to one cylinder through port A and duct 1 and the slot 45 connecting them, the same slot will conduct air from port A to duct 2 of the next cylinder to the right (Figure 17) when the valve is reversed. The cylinders marked 1, 2 and 3 may be referred to as first, second and third cylinders; while the ports marked A, B and C may be referred to as first, second and third ports. It is pointed out that the disk 38 and spider 37 do not move, except when the motor is reversed.

It will be presumed that the motor is started rotating in a clockwise direction with the valve turning in the direction of the arrows (Figures 5 and 16). Rotation being imparted to the cap 39 the first port 46 or A in Figure 16, to which air is being supplied and which supplies it to duct 1. Figure 16 will be covered before the piston completes its power stroke. The second port 46 or B in Figure 16 is next uncovered so as to admit

air to the duct 2 in Figure 16 of the second cylinder and the channel 50 of the cap moves over the first port 46 or A in time to establish communication between the duct 36 or 1, Figure 16 of the first cylinder and exhaust chamber 16 by way of the opening 47, sleeve 40, port 40', and passage 19.

80 After the second cylinder has operated the continued rotation of the valve cap 39 uncovers the third port 46 or C in Figure 16 of the duct 36 or 3 in Figure 16 of the third cylinder. The channel 50 will also move over the second port 46 or B in Figure 16 and thus exhaust the second cylinder. The air pressure holding the valve members seated and the exhaust air passing through the channel 50 assures against air leaks, obviates the use of packings, and makes for more efficient operation. The exhaust passing to the chamber 16 and escaping through the ports to atmosphere is excluded from the crank case 1.

85 By observing Figure 5, it will be noted that by reason of the recess 53, air is supplied to only one of the ports 46 at a time, and the other two ports are cut off from the air supply and are either covered by the back face of the cap 39 or are in communication with the channel 50, which in turn is in constant communication with the exhaust chamber 16. This is true except at the instant the gap 53 in the cap 39 is uncovering one port and covering the trailing port, which will occur when the advance piston is at top of dead center. The slots 45 in the spider 37 establish communication between particular ports and particular ducts and, therefore, one slot will be conducting air from one port to one duct, while the other two slots will be conducting air from the other two ducts to the other two ports.

90 It is obvious that if the upper left hand slot 45 in Figure 16 is conducting air from the port A to the duct 1, the right hand slot 45 in Figure 115 16 will be conducting exhaust air from the duct 2 to the port B. Now, should the spider be shifted in a counter-clockwise direction, the right hand slot in Figure 16 will be moved to the left, whereby port A will be connected with duct 2. Duct 2, 120 being connected with a cylinder in which the piston is traveling outwardly on its exhaust stroke, it is obvious that when the port A is connected with said duct, air will be supplied to said cylinder, whereby the travel of the piston will be 125 reversed and also the direction of rotation of the motor will be reversed. In order to reverse the direction of rotation of the motor, it is merely necessary to swing the lever 44 from the position shown in Figure 16 to that shown in Figure 130 17. This will rotate the shaft 43, which in turn will rotate the elements 42, 41 and 40 (Figures 4 and 6), whereby the spider 37 will be moved in a counter-clockwise direction (Figures 16 and 17).

135 During the initial movement of the spider the pin 48 will travel in the bottom of the opening 47 without imparting rotation to the disk 38. This initial movement of the spider will move the solid webs or legs, which separate the ends of the slots 45, in a counter-clockwise direction 140 and cause them to pass under the stationary ports A, B and C (Figure 16), whereby communication between each port and the slot extending counter-clockwise therefrom will be broken, and communication between each port 145 and the slot following said port will be established. Referring to Figure 16, where air is being supplied to duct 1 from port A, upon the shifting, air will be supplied from port A to duct 2. During the initial movement of the spider the 150

disk 38 has remained stationary, and the pin 48 is traveling in the opening 47; but when the pin 48 reaches the other side of the opening 47, the disk 38 will be shifted in a counter-clockwise direction until arrested by the stud 20', as shown in Figure 17. It is necessary to move the disk 38 to position the ports with relation to the recess 53 of the cap and thereby give the motor a lead in advance sufficient to supply air to reverse it. When the reversing is effected, as above described, the cap 39 is traveling in a clockwise direction, but as soon as the reverse is completed, said cap will begin to travel in a counter-clockwise direction and, therefore, it is necessary to shift the port A so as to give the second cylinder connected with the port 2 sufficient advance or lead.

It is pointed out that only a single set of ports is used for driving in either direction and this greatly simplifies the reversing means. By locating the reversing actuators in the exhaust chamber and closing off said chamber from the crank case, any leaks around the shaft 43 would be of no consequence and thus packing is not required. The terminating of the crank shaft and within the dome 49 of the valve cap permits the housing 20 to be made imperforate, except for the fluid pressure entrance. It also obviates by-passing of the pressure fluid along the crank shaft. The crank shaft being entirely in the exhaust passage, no packing is required and leaking would not interfere with the operation. The valve members being seated by the pressure fluid, obviate leaking therebetween.

In order to make the motor useful for its purpose, it must be made small and light in weight. The single set of ports in the disk 38 permits the making of a very small valve, which would be impossible if two sets of ports were necessary. It is preferable to extend the train of gears 13 along the cylinder 2, which is diametrically opposite from the handle 25. This not only balances the motor, but it enables the shaft 14 to be connected with devices and the same operated in corners and comparatively close angles. By keeping the exhaust fluids and the pressure fluids entirely separated, as well as by closing off the exhaust chamber from the crank case, the chance of leakage, whereby these fluids would commingle, is reduced to a minimum and a higher efficiency is obtained.

The description which has been given recites more or less detail of a particular embodiment of the invention, which is set forth as new and useful; however, I desire it understood that the invention is not limited to such exact details of construction, because it is manifest that changes and modifications may be made, within the scope of the appended claims, without departing from the spirit of the invention.

What I claim and desire to secure by Letters Patent, is:

1. A pneumatic motor comprising, a crank case, cylinders extending from said case, a crank shaft journaled in said case, pistons operating in said cylinders and connected with said crank shaft, a stationary exhaust chamber at one side of the crank case and closed off therefrom, a fluid pressure chamber at the same side of said case and outwardly of said exhaust chamber, the exhaust chamber having an opening to atmosphere, ducts leading from the pressure chamber to the outer ends of the cylinders, a rotating valve mechanism in the pressure chamber connected directly to and driven by the crank shaft, said valve mech-

anism including a member for admitting pressure fluid to the ducts and for conducting exhaust fluids from the ducts to the exhaust chamber, reversing means for reversing the valve mechanism located in the exhaust chamber and connected with the valve mechanism, and an exterior operator connected with the reversing means.

2. A pneumatic motor comprising, a crank case, cylinders extending from said case, a crank shaft journaled in said case, pistons operating in said cylinders and connected with said crank shaft, a stationary exhaust chamber at one side of the crank case and closed off therefrom, a fluid pressure chamber at the same side of said case and outwardly of said exhaust chamber, the exhaust chamber having an opening to atmosphere, ducts leading from the pressure chamber to the outer ends of the cylinders, a valve mechanism in the pressure chamber comprising a spider having openings registering with the ducts and a disk having ports registering with the openings of the spider and a rotating cap having an opening for exposing the ports of the disk and a channel, the openings of the spider being in constant communication with the ducts, a passage extending from the exhaust chamber constantly open to the channel of the valve cap, a driving connection between the crank shaft and the valve cap, means within the pressure chamber for holding the cap in contact with the disk, reversing means in the exhaust chamber connected with the spider, an exterior operator connected with the reversing means, and a connection between the spider and the disk for rotating the latter when the spider is rotated.

3. A pneumatic motor comprising, a crank case, cylinders extending from said case, a crank shaft journaled in said case, pistons operating in said cylinders and connected with said crank shaft, a stationary exhaust chamber at one side of the crank case and closed off therefrom, a fluid pressure chamber at the same side of said case and outwardly of said exhaust chamber, the exhaust chamber having an opening to atmosphere, ducts leading from the pressure chamber to the outer ends of the cylinders, a valve mechanism in the pressure chamber comprising a spider having openings registering with the ducts and a disk having ports registering with the openings of the spider and a rotating cap having an opening for exposing the ports of the disk and a channel, the openings of the spider being in constant communication with the ducts, a passage extending from the exhaust chamber constantly open to the channel of the valve cap, a driving connection between the crank shaft and the valve cap, means within the pressure chamber for holding the cap in contact with the disk, reversing means in the exhaust chamber connected with the spider, an exterior operator connected with the reversing means, a connection between the spider and the disk for rotating the latter when the spider is rotated, and spring means for holding the spider against the inner wall of the pressure chamber.

4. A pneumatic motor comprising, a crank case, cylinders extending from said case, a crank shaft journaled in said case, pistons operating in said cylinders and connected with said crank shaft, a fluid pressure chamber carried by the crank case, ducts leading from said chamber to the outer ends of the cylinders, an exhaust passage leading from the pressure chamber, a rotatable valve spider in the chamber having openings in communication with the ducts, a valve disk having a single set of ports registering with

the openings of the spider, a shifting connection between the spider and the disk, the spider and disk having openings registering with the exhaust passage, a rotating cap connected with the crank shaft and having an opening for exposing the ports of the disk in the pressure chamber and a channel for connecting said ports with the opening to the exhaust passage, and a single reversing means connected with the spider.

5 10 As a sub-combination in a multi-cylinder pneumatic motor, a valve mechanism comprising, a rotatable spider having a central fluid passage and arcuate fluid passage openings surrounding said central openings, a rotatable disk having a fluid-tight bearing on the spider and provided with a single set of ports in registration with the arcuate fluid passages of the spider and a central opening in registration with the central opening of the spider, a connection between the spider and the disk arranged to permit initial rotation of the spider and subsequent rotation of the disk by the spider, a rotating cap fitting on the disk having an opening for successively exposing the ports of the disk and a channel for connecting said ports with the central opening of the disk, and a single reversing means connected with the spider.

15 20 25 30 35 40 45 50 55 60 65 70 75 80 85 90 95 100 105 110 115 120 125 130 135 140 145 150

6. As a sub-combination in a multi-cylinder pneumatic motor, a valve mechanism comprising, a rotatable spider having a central fluid passage and arcuate fluid passage openings surrounding said central openings, a rotatable disk

having a fluid-tight bearing on the spider and provided with a single set of ports in registration with the arcuate fluid passages of the spider and a central opening in registration with the central opening of the spider, a connection between the spider and the disk arranged to permit initial rotation of the spider and subsequent rotation of the disk by the spider, a rotating cap fitting on the disk having an opening for successively exposing the ports of the disk and a channel for connecting said ports with the central opening of the disk, and a single reversing means connected with the spider.

7. A pneumatic motor comprising, a crank case, cylinders extending from said case, a crank shaft journaled in said case, pistons operating in said cylinders and connected with said crank shaft, a stationary exhaust chamber at one side of the crank case and closed off therefrom, a fluid pressure chamber at the same side of said case and outwardly of said exhaust chamber, the exhaust chamber having an opening to atmosphere, ducts leading from the pressure chamber to the outer ends of the cylinders, a valve mechanism comprising a plurality of members having fluid passages communicative with the exhaust chamber, the ducts and the pressure chamber, and means in the exhaust chamber connected with the valve mechanism for reversing the same.

CHARLES S. TANKERSLEY.
